Primary Examiner — Jennifer Rivard*Assistant Examiner* — April Rivas(74) *Attorney, Agent, or Firm* — Intellectual Property Law Offices of Joel Voelzke, APC**CLAIM**

The ornamental design for a toy container, as shown and described.

DESCRIPTION

FIG. 1 is an front, top, right oblique view of a toy container showing our new design;

FIG. 2 is a front elevation view thereof;

FIG. 3 is a rear elevation view thereof;

FIG. 4 is a side elevation view thereof, showing the left side;

FIG. 5 is side elevation view thereof, showing the right side;

FIG. 6 is a top plan view thereof; and,

FIG. 7 is a bottom plan view thereof.

A separation line is shown in a broken line for illustration purposes only and forms no part of the claimed design.

1 Claim, 6 Drawing Sheets(56)
